LATTICE DISPLAY

Ned Burr, Chicago, Ill., assignor to Chicago Cardboard Company, Chicago, Ill., a corporation of Illinois

Application July 22, 1940, Serial No. 346,792

2 Claims. (Cl. 40—124.1)

This invention relates in general to a collapsible display comprising two or more pieces of material which are movable apart and connected at their proximate edges by an extensible and collapsible strip or sheet having related slots or slits therein which form an attractive connecting lattice-work between the parts.

An important object of the invention is in the provision of a folding or collapsible display of cardboard or other similar material having adjacent parts which are movable in spaced relation to each other but which are connected by a piece of material having cuts or slits therein extending parallel and overlapping or staggered with respect to each other in adjacent lines or courses so that when the parts are separated the connecting material will form a lattice or an open network permitting a considerable separation of the parts, depending upon the width of the lattice-work and at the same time permitting a return or collapse of the parts without lateral displacement of the parts by such movement.

A further object of the invention is to provide a display in which one part is offset from another by means of lattice-work connected thereto with means for releasably holding the parts and the lattice-work in such extended position.

A still further object of the invention is in the provision of a display having parts connected and movable apart to a limited extent by means of a connected lattice-work, and in the provision of distending and limiting means for confining the extended and collapsing movement within the proper limits.

Other objects of the invention will appear in the specification and will be apparent from the accompanying drawings, in which,

Fig. 1 is a plan view of a circular display constructed in accordance with this invention;

Fig. 2 is a sectional distended view of the display taken on the line 3—3 of Fig. 1;

Fig. 2a is a sectional view of the parts shown in Fig. 2 in flat folded position;

Fig. 3 is a sectional distended view of the display as taken on the lines 4—4 of Fig. 1;

Fig. 4 is a side elevation of a portion of the display illustrating the extension of the lattice-work;

Fig. 5 is a detail perspective illustrating the display extending and limiting means;

Fig. 6 is a section taken on the line 6—6 of Fig. 5; and

Fig. 7 shows a blank as cut to form one of the parts of the display.

This invention relates to a novel display con-

struction by which two parts ordinarily movable apart for display and collapsed together for storing and shipping are connected by a contrasting piece of material such as a strikingly colored lattice member which will expand and collapse to a limited extent without tearing or disruption, and will maintain the parts in corresponding position without relative lateral or rotative movement. Although lattice-work made of paper or other similar material is known and used, the present invention relates particularly to its use in a display and to the means for controlling and limiting the extending and collapsing thereof.

Referring now more particularly to the drawings, the invention is described in connection with a display having a circular center part 10, an outer circular rim 11, and an interposed lattice ring 12. While this construction is merely illustrative of the type of displays or constructions which may be included in the present invention, the particular form shown is also desirable as a display, and may have parts of other shapes and forms rather than the circular pieces as shown.

The lattice ring or member comprises a sheet such as paper, cardboard or other flexible material, having solid or imperforate edges 13 and 14 with an intermediate lattice portion formed by parallel slits 15 cut through the material and the cuts arranged in parallel lines, the cuts of one line being staggered or offset with the cuts of the adjacent lines so that a connected network is formed which is capable of expansion and contraction to a limited extent without tearing the material and by attaching the imperforate edges, an attractive network is provided for connecting two adjacent parts without lateral or rotative movement of one part with respect to the other.

One imperforate edge 13 is attached to the under-side of the margin of the part 10 and the other imperforate edge 14 is attached to the rear side of the outer part 11, or is included as shown, between the part 10 and a back plate 16 which constitutes a support for the entire display. The edges 13 and 14 are adhesively attached or connected to the parts in any other desired manner, the intermediate latticed construction preferably lying flat between the connected parts when they are in collapsed position, and extending angularly between the parts when they are extended.

By making the slits 15 short and closely spaced in each row, staggered with respect to those in adjacent rows, the surface of the inclined lattice work appears substantially continuous when viewed from the front, the small apertures formed

by the slits being apparent from the side or edge of the display.

In order to control the extending movement of the lattice connection, the back plate 16 is cut and scored at the center behind the extensible display part 10, as clearly shown in Fig. 7, to provide extension props 17 and limiting members 18. Each extension prop is substantially rectangular in outline, is hinged to the back plate by a partial severing line 19, the outer edge 20 engages the inner or rear side of the central display plate or part 10 to hold it outwardly and to distend the lattice-work a distance equal to the width of the prop.

As shown, the props 17 and limiting members 18 are alternated and are adjacent each other, each limiting member comprising connected hinged members 21 and 22 and an outer attaching member 23, all connected by partially cut lines 24, 25 and 26 which form the hinges. At the ends of each attaching member 23 are notches 27 adapted to be engaged by the outer extremities of the next adjacent extension props 17 and this end extension of each of the attaching members being therefore cut out of the edges of the adjacent props forming recesses 28 in the props which constitute finger-engaging portions for raising or disengaging the props in collapsing the display.

Each attaching member 23 is adhesively or otherwise permanently secured to the back or under side of the central display part 10 and the hinging members 21 and 22 are together of a slightly greater width than the width of the extension props 17 so that when the props are in place, extending the lattice-work to its greatest extent, the members 21 and 22 are not in alignment but preserve an angular position with respect to each other as shown more clearly in Fig. 3, and also with respect to the prop 17, as shown in perspective in Fig. 2. Due to the resilience of the material and the hinging connection of these parts, this resilience permits the props to be yieldingly pushed into place against the stop notches 27 and disengaged therefrom, limiting the separation or opening movement of the lattice-work and maintaining it resiliently in its extended position.

While this lattice construction is shown in a circular display in which the parts are separated an equal amount all around, a similar lattice may be used to connect any two parts for display purposes and greater or less separation may be provided by making the lattice-work of different widths as desired. In any foldable or collapsible display it is desirable to limit the extending movement of the lattice-work, as it is easily torn if extended too far, and to provide a resilient prop for holding it in distended position which may be easily disengaged for collapsing the display.

I claim:

1. In a lattice display, a central part, a supporting back extending outwardly beyond the central member, a flexible latticed sheet connected at its edges to the central part and outwardly therefrom to the outer edge of the supporting back, the intermediate portion of the lattice sheet having slits to form an open lattice-work when the central part is moved relative to the back, hinged tongues formed in the back member at the rear of the central part and covered thereby to engage and hold the central part in a projected position from the back, distending the lattice-work, and a hinged tongue also formed of the material of the back and connected to the central part within the lattice-work for limiting the projected movement of the central part and for yieldingly holding it in place.
2. A structure in accordance with claim 1 in which the projecting tongues and the hinged limiting means are alternately disposed and are cut from the central portion of the back to form an attaching portion which is secured to the said central part, this attaching portion being cut from the outer edges of the distending tongues and forming finger-hold portions therein, and the said attachment portions having shoulders forming stops for engaging and limiting the extremities of the distending tongues in their distending movement, the tongues being held in engagement therewith by the resilience of the said limiting means.

NED BURR.
